(57) **CLAIM**

The ornamental design for a prosthetic as shown and described.

DESCRIPTION

FIG. 1 is a perspective view of a prosthetic showing my new design;

FIG. 2 is a front view thereof, the rear view being a mirror image;

FIG. 3 is a top view thereof;

FIG. 4 is a bottom view thereof;

FIG. 5 is a left side view thereof; and,

FIG. 6 is a right side view thereof.

The broken lines illustrate structure or features which form no part of the claimed design.

The dot-dash broken lines illustrate boundaries which form no part of the claimed design.

1 Claim, 6 Drawing Sheets
